United States Patent Office

Des. 176,357
Patented Dec. 13, 1955

176,357

AUTOGRAPHIC REGISTER

Russell Katz, Hamilton, Ohio, assignor to Paul Benninghofen and F. B. Diesbach, Hamilton, Ohio, as trustees

Application February 3, 1954, Serial No. 28,828

Term of patent 14 years

(Cl. D64—11)

I claim:

The ornamental design for an autographic register, substantially as shown.
